UNITED STATES PATENT OFFICE.

RUDOLPH MILLER, OF ST. MICHAEL, PENNSYLVANIA, ASSIGNOR OF ONE-HALF TO
LORENZ KLAGG, OF ST. MICHAEL, PENNSYLVANIA.

AUTOMATIC GAS LOCK.

1,419,884.

Specification of Letters Patent. Patented June 13, 1922.

Application filed October 1, 1921. Serial No. 504,721.

To all whom it may concern:

Be it known that I, RUDOLPH MILLER, a citizen of the United States, residing at St. Michael, in the county of Cambria and State of Pennsylvania, have invented certain new and useful Improvements in Automatic Gas Locks, of which the following is a specification.

This invention relates to the feed conductors of gas burners, and has for one of its objects to provide a simply constructed attachment whereby the flow of gas is automatically cut off in the event of the reduction of pressure below a certain predetermined degree, or in event of the flow being interrupted from any cause, and danger of the restoration of the flow through an unlighted burner, thus prevented.

Another object of the invention is to provide a device of this character which may be adapted to burner conductors of various forms and sizes without material structural change in the burner or in the conductor.

With these and other objects in view the invention consists in certain novel features of construction as hereinafter shown and described and then specifically pointed out in the claims, and in the drawings illustrative of the preferred embodiment of the invention,

Figure 1 is a vertical sectional side elevation.

Fig. 2 is a vertical sectional elevation at right angles to Fig. 1.

Fig. 3 is a transverse section on the line 3-3 of Fig. 1.

Fig. 4 is a transverse section on the line 4-4 of Fig. 1.

Fig. 5 is a side elevation with the covering cap of the spring removed.

Fig. 6 is a plan view of the parts shown in Fig. 5.

Fig. 7 is a perspective view of the locking lever and its shaft, enlarged.

Fig. 8 is a perspective view, enlarged, of the trip lever and its shaft.

Fig. 9 is a perspective view, enlarged, of the releasing key.

The improved device includes a casing or shell preferably formed in separable parts, a main hollow body portion 10 having a valve plug 11 mounted therethrough, the

plug having a gas passage 12 and provided with a spring, indicated at 13, operating to yieldably hold the plug in closed position or with its passage in engagement with an unperforated portion of the body as indicated in Figures 1 and 5.

The valve plug 11 is provided with a laterally directed combined stop and trip pin 14 which engages a shoulder 15 within the casing 10 when in one position, as shown in Figure 1, and adapted to trip a releasing mechanism when in another position, as hereafter explained.

The casing 10 is formed with a threaded extension 16 to receive the lower portion of the conductor for the flow of gas, a portion of the conductor being represented at 17.

At its upper side the casing 10 is extended to form a chamber 18.

Supported within the portion of the chamber 18 next to the casing or shell 10, is an oblong supporting frame 20 in which two shafts 21 and 22 are mounted, while a third shaft 23 is supported by ears 24 rising from the frame 20.

Extending from the shaft 21 is an arm 25 having an off-set forming a stop shoulder 26 intermediate the ends with which the pin 14 engages when the plug 11 is turned into opening position, as hereafter explained.

Extended from the shaft 22 is a cam or stud 27 adapted to engage the lever arm 25 and elevate the same to release the shoulder 26 from engagement with the pin 14.

Extending from the shaft 23 is a curved arm 28 having an enlargement 29 at its free end, the arm bearing over the shaft 23 when in lower position as shown in full lines in Figure 1.

The shaft 23 extends gas tight through one wall of the chamber 18 and is adapted to receive a turning key, represented at 30.

The shaft 23 is also provided with a cam lug 31, preferably in the form of a crank, and adapted to elevate the arm 28 into the position shown by dotted lines in Figure 1, when the shaft 23 is rotated.

By this arrangement when the shaft 23 is rotated by applying the key device 30 thereto, the arm 28 is elevated and the cam lug 27 depressed and disposed in the position shown by dotted lines in Figure 1, and thereby

correspondingly depressing the arm 25 into the position shown by dotted lines in the same Figure 1.

Extending upwardly above the chamber 5 member 18 is a tubular member 32 having a threaded portion 33 at the upper end to receive the continuation of the service pipe represented at 34.

A portion of the interior of the member 10 33 is formed with longitudinally directed ribs 35 and with radial ribs 36 at the upper end of the member 33 merging into the ribs 35. By this means a plurality of longitudinally and laterally directed channels 15 are produced on the interior of the member 33.

Slidably disposed within the member 33 and in contact with the ribs 35 is a hammer or trip device 37, sufficiently light to be held in elevated position by the pressure of the upwardly flowing gas, and sufficiently heavy to fall by gravity and trip the member 28 in event of the reduction or stoppage of the flow of the gas.

25 When the gas is to be turned on, the key 30 is applied to the shaft 23 and the latter rotated one-fourth of a revolution to cause the crank member 31 to elevate the arm 29 and correspondingly depress the cam member 27 and dispose them into the position shown by dotted lines in Figure 1.

This action will release the arm 25 and permit its spring 25' to pull it downward into the position shown by dotted lines in 35 Figure 1 with the shoulder 26 in the path of the pin 14, so that when the plug 11 is rotated to "open" the valve the pin will engage the portion of the arm 25 between the shaft 21 and the shoulder 26 and elevate the 40 arm 25 and pass the shoulder 26 when the arm will be returned by its spring 25' to its lower position, and thus lock the plug 11 from retrograde movement. The lateral pressure of the pin 14 under the influence 45 of the spring 13 will be sufficient to hold the arm 29 in its elevated position so that the shaft 23 may be returned to its initial position as shown in full lines in Figure 1 without releasing the arm 29, which remains 50 poised as shown by dotted lines in the same figure.

The upward flow of the gas passes through the chamber 18 and extension 33 and around the floating member 37 and the 55 weight of the member 37 is so gaged that the normal pressure of the gas will be sufficient to maintain the float member in its upper position against the inturned portion of the casing 33, the flow of the gas not being interrupted by the float owing to the presence of the spaced ribs 35, as will be obvious.

If the gas ceases to flow for any reason, or if the pressure is reduced below the normal, the float member will fall by gravity

and depress the arm 29 and cause the cam member 27 to be elevated and correspondingly elevate the arm 25 against the resistance of the spring 25' and release the pin 14 and permit the spring 13 to rotate the 75 plug 11 until the pin 14 strikes the shoulder 15, the valve being thus automatically closed and all danger of the flow of gas to an unlighted burner obviated.

By this means the free flow of the gas 75 is not interfered with, while at the same time all danger of the flow of gas through an unlighted burner is effectually and automatically obviated.

The device is simple in construction, can 80 be made of any required size to apply to gas conductors of various sizes.

The preferred embodiment of the invention is disclosed in the drawings and set forth in the specification, but it will be 85 understood that modifications within the scope of the claimed invention may be made in the construction without departing from the principle of the invention or sacrificing any of its advantages.

Having thus described the invention what is claimed as new is:—

1. A device of the class described comprising a valve including a rotative perforated plug having an outwardly directed stop, a 95 rock shaft carrying a lock lever having an intermediate stop shoulder to engage the plug stop to hold the plug in open position, another rock shaft carrying a trip means to release said lock lever, a floating member 100 adapted to be maintained in elevated position by the normal gas pressure, and adapted to fall by gravity in event of the abnormal reduction of the gas pressure and actuate the releasing means and permit the plug to move into closed position.

2. In a device of the character described, a valve including a rotative perforated plug, means for yieldably maintaining the plug in closed position, a rock shaft carrying a lock 110 lever adapted to hold said plug in open position against the resistance of the yieldable closing means, another rock shaft carrying a trip device operative to release said locking means, and a floating member retained in inoperative position by the normal pressure of the gas flowing through the plug and adapted to depress said trip device and release said locking means when the gas ceases to flow or when the pressure is reduced below the normal.

3. In a device of the class described, a valve casing, a chamber communicating with the casing, a perforated plug rotative in the casing, means for yieldably maintaining the plug in closed position, a frame within said chamber, a locking member swingingly connected to said frame and operative to hold said plug in open position against the resistance of said yieldable means, a trip device 125

swingingly connected to said frame and operative to release said locking member, a guide casing communicating with said chamber and having inwardly directed spacing 5 ribs, a float member movable in said guide casing and against said guide ribs and retained in inoperative position by the normal pressure of the gas flowing through the plug and adapted to depress said trip device and release said locking means when 10 the gas ceases to flow or when the pressure is reduced below the normal.

In testimony whereof, I affix my signature hereto.

RUDOLPH MILLER.
